H. P. EVANS ET AL

FUEL ECONOMIZER FOR GAS FIRED STOVES AND THE LIKE

Filed July 12, 1922

FIG. 1

FIG. 2

Inventor
H.P. Evans
H.S. Standon
By Marks Deckatty's

UNITED STATES PATENT OFFICE.

HENRY PERCY EVANS, OF ABBOTSFORD, NEAR SYDNEY, AND HENRY SNOWDON STANDEN, OF WAVERLEY, NEAR SYDNEY, NEW SOUTH WALES, AUSTRALIA.

FUEL ECONOMIZER FOR GAS-FIRED STOVES AND THE LIKE.

Application filed July 12, 1922. Serial No. 574,588.

To all whom it may concern:

Be it known that HENRY PERCY EVANS and HENRY SNOWDON STANDEN, subjects of the King of Great Britain and Ireland, residing, respectively, at "Wymston," Wymston Parade, Abbotsford, near Sydney, New South Wales, Australia, and Cross Street, Waverley, near Sydney aforesaid, have invented new and useful Improvements in 10 Fuel Economizers for Gas-Fired Stoves and the like, of which the following is a specification.

This invention relates to fuel economizer apparatus which is usable in connection with 15 gas-fired stoves and the like.

The apparatus comprises a metal plate which is adapted to be set over a gas stove burner or jet and to hold thereon in separate 20 positions two or more pots or similar receptacles to which heat is conveyed from the one burner or jet. The plate is constructed specially to enable proper distribution of 25 the flame from the burner or jet to the separate receptacles carried thereon as well as to permit proper positioning of the receptacles on the plate.

Referring to the accompanying drawings, Fig. 1 is a plan view of the top or upper side 30 of the plate, and Fig. 2 a plan view of the bottom or lower side thereof.

The metal plate is preferably cast, and is of suitable thickness, and its dimensions are such to permit its central portion to overlie a gas burner, whilst the plate is resting on a 35 stove or the like, and the receptacles to which heat is to be conveyed are resting partly on the central portion and the outer portions of the plate and if necessary partly on the stove or the like. It is preferred to 40 construct the plate with a central circular portion 1 having the arms 2 radiating therefrom, such arms being disposed in relation to the central portion and to adjacent arms, whereby an opening 3 will be provided 45 between each of the said arms. The outer ends of the arms 2 are preferably curved. Disposed around the outer ends of the central portion 1 of the lower face of the plate between the arms 2 are a series of 50 grooves 4; these grooves taper from said outer ends. There are also larger grooves 5 at the sides of the arms 2 and flanking the grooves 4. The portions of the central part

1 of the plate in which the taper grooves 4 are formed are curved and project into the 55 openings 3 between the arms 2.

On the upper face of the plate is a rib; this rib is of larger dimensions at its central part 7 which is located on the portion 1 of the plate than the fins 6 which project 60 therefrom and extend partly along the arms 2. The said rib and fins are arcuated and serve as abutment stops for the lower edges 65 of pots or similar receptacles, set on the plate for the purpose of having heat transmitted thereto, as well as reinforcements for the plate.

In operation, the plate is set on a stove or the like with the central portion 1 thereof located directly over the gas burner or jet 70 of the stove or the like. If there are three openings 3 provided in connection with the plate three pots or similar receptacles to which heat is to be conveyed may then be placed on the plate, the rib 7 and fins 6 serving 75 as separating stops for the individual receptacles. Flame from the burner or jet is thus spread by the central portion 1 of the plate and is projected into the openings 3 and under the receptacles to be heated. The 80 grooves 4 and 5 serve to conduct the flame from the central portion 1 of the plate to the individual receptacles, and the heat of the flame from the one burner or jet of the stove or the like is thus evenly distributed 85 to the separate receptacles.

What we claim as our invention and desire to secure by Letters Patent is:—

1. A fuel economizer for gas-fired stoves and the like consisting of a metal plate, said plate having a central portion adapted to overlie the flame of a fuel burner, spaced arms radiating from said central portion and providing openings between said arms, the outer edges of said central portion extending into said openings between said arms and adapted to deflect flame projected onto said central portion from a gas burner under receptacles placed on said plate over said openings.

2. A fuel economizer for gas-fired stoves and the like consisting of a metal plate, a central portion for said plate adapted to be set over a gas-burner, a plurality of arms radiating from said central portion and disposed in relation thereto and to adjacent

- arms whereby openings are provided between said arms, said central portion having at its outer edges located between said arms a series of grooves adapted to deflect 5 flame projected onto the said central portion from said gas burner to the separate openings between said arms, whereby receptacles set on said plate over said openings may be separately heated.
- 10 3. In a fuel economizer for gas-fired stoves and the like as set forth in claim 1 hereof, the construction in which one face of the metal plate is formed with an arcuate rib and fins serving as a separating stop 15 for receptacles set on said plate for the purpose of being heated.
4. A fuel economizer for gas-fired stoves and the like comprising a metal plate, a central portion for said plate adapted to 20 be set over a gas-burner to serve as a gas distributor, three or more arms projecting from said central portion whose outer edges extend into openings provided between each 25 said arms, flame deflecting grooves in said outer edges on one face of said plate, and a fin rib located on the other face of said plate whose centre is thickened and whose fins extend from said centre and along part 30 of said arms whereby said fin-rib is adapted to serve as a separating stop for individual receptacles placed on said plate over

said openings for the purpose of being heated.

5. In a fuel economizer for gas-fired stoves and the like consisting of a plate 35 furnished with a central portion and with three or more arms radiating therefrom and disposed in relation to each other and to said central portion whereby an opening will be provided between each said arms, 40 the combination of a fin-rib located on one face of said plate adapted to act as a separating stop for receptacles placed over said openings in said plate and as a reinforcement for said plate. 45

6. A fuel economizer comprising a central body part adapted to overlie the flame of a fuel burner to cause the deflection of said flame toward the edge of the body member, arms radiating from said body member, 50 the top surfaces of said body member and said arms being adapted to support a plurality of cooking vessels and said arms being arranged in spaced relation to provide openings thereunder through which the 55 flame deflected by said body member may issue and play upon the bottoms of the cooking utensils supported over said openings.

In testimony whereof we have signed our names to this specification.

HENRY PERCY EVANS.

HENRY SNOWDON STANDEN.
